CANDLESTICK

Samuel W. Perkins, Palo Alto, Calif.

Application November 3, 1952, Serial No. 22,106

Term of patent 3½ years

(Cl. D48—2)

To all whom it may concern:

Be it known that I, Samuel W. Perkins, a citizen of the United States, residing at Palo Alto, in the county of Santa Clara and State of California, have invented a new, original, and ornamental Design for a Candlestick, of which the following is a specification, reference being had to the accompanying drawing, forming a part thereof.

In the drawing:

Fig. 1 is a perspective view of a candlestick, embodying my new design.

Fig. 2 is an end elevation of the candlestick seen from line 2—2 in Fig. 1.

Fig. 3 is an elevation of the opposite end of the candlestick of Fig. 2.

Fig. 4 is a bottom plan view of Fig. 2.

Fig. 5 is a top plan view of Fig. 3.

Fig. 6 is a side elevation of the candlestick of Fig. 5 and taken from line 6—6 therein.

The dotted line showing of candles in Fig. 1 is only for the purpose of illustration.

I claim:

The ornamental design for a candlestick, as shown and described.

SAMUEL W. PERKINS.
